UNITED STATES PATENT OFFICE

149,975

DESIGN FOR A PNEUMATIC GAUGING DEVICE

Frederick L. Rupley, Cincinnati, Ohio, assignor to
Merz Engineering Company, Indianapolis, Ind.,
a corporation of Indiana

Application July 22, 1946, Serial No. 131,793

Term of patent 7 years

(Cl. D52—1)

To all whom it may concern:

Be it known that I, Frederick L. Rupley, a citizen of the United States and a resident of Cincinnati, in the county of Hamilton and State of Ohio, have invented a new, original, and ornamental Design for a Pneumatic Gauging Device, of which the following is the specification, reference being had to the accompanying drawings, forming part thereof, wherein:

Figure 1 is a front elevation of a pneumatic gauging device embodying my new design;

Figure 2 is a rear elevation;

Figure 3 is a plan view;

Figure 4 is a view taken from the right side of Figure 1;

Figure 5 is a view taken from the left side of Figure 1; and

Figure 6 is a perspective view.

The essential features of my design reside in the portion shown in full lines.

I claim:

The ornamental design for a pneumatic gauging device, substantially as shown and described.

FREDERICK L. RUPLEY.
